(57) **CLAIM**

The ornamental design for a stand for mobile device, as shown and described.

DESCRIPTION

FIG. 1 is an upper side view of a stand for mobile device in accordance with a first embodiment of the invention;

FIG. 2 is a rear view thereof;

FIG. 3 is a right side view thereof;

FIG. 4 is a left side thereof;

FIG. 5 is a lower side view thereof;

FIG. 6 is a front view thereof;

FIG. 7 is a rear-left perspective view of the stand for mobile device in the closed or flat state in accordance with the first embodiment of the invention;

FIG. 8 is a rear-left perspective view of the stand for mobile device in the open or standing state in accordance with the first embodiment of the invention;

FIG. 9 is an upper side view of the stand for mobile device in accordance with a second embodiment of the invention;

FIG. 10 is a rear view thereof;

FIG. 11 is a right side view thereof;

FIG. 12 is a left side view thereof;

FIG. 13 is a lower side view thereof;

FIG. 14 is a front view thereof;

FIG. 15 is a rear-left perspective view of the stand for mobile device in the closed or flat state in accordance with the second embodiment of the invention;

FIG. 16 is a rear-left perspective view of the stand for mobile device in the open or standing state in accordance with the second embodiment of the invention;

FIG. 17 is an upper side view of the stand for mobile device in accordance with a third embodiment of the invention;

FIG. 18 is a rear view thereof;

FIG. 19 is a right side view thereof;

FIG. 20 is a left side view thereof;

FIG. 21 is a lower side view thereof;

FIG. 22 is a front thereof;

FIG. 23 is a rear-left perspective view of the stand for mobile device in the closed or flat state in accordance with the third embodiment of the invention; and,

(Continued)

FIG. 24 is a rear-left perspective view of the stand for mobile device in the open or standing state in accordance with the third embodiment of the invention.

The broken lines shown in the figures are for the purpose of illustrating structure that forms no part of the claimed design.
